UNITED STATES PATENT OFFICE.

RICHARD HENRY WHITEHEAD, OF NEW HAVEN, CONNECTICUT, ASSIGNOR TO NEW HAVEN CLOCK CO., OF NEW HAVEN, CONNECTICUT, A CORPORATION.

DESIGN FOR A WATCHCASE.

Application filed January 5, 1924. Serial No. 8,246. Term of patent 14 years.

To all whom it may concern:

Be it known that I, RICHARD H. WHITEHEAD, a citizen of the United States, residing at New Haven, in the county of New Haven and State of Connecticut, have invented a new, original, and ornamental Design for a Watchcase, of which the following is a specification, reference being had to the accompanying drawing, forming part thereof.

Fig. 1 is a face view of a watch case showing my new design.

Fig. 2 is a side view of the same.

I claim:

The ornamental design for a watchcase as shown.

RICHARD HENRY WHITEHEAD.
